(57) **CLAIM**

I claim the ornamental design for a convertible scooter, as shown and described.

DESCRIPTION

FIG. 1 is a top perspective view of a first configuration of a convertible scooter according to the new design.

FIG. 2 is a bottom perspective view of the convertible scooter shown in FIG. 1.

FIG. 3 is a right side view of the convertible scooter shown in FIG. 1.

FIG. 4 is a left side view of the convertible scooter shown in FIG. 1.

FIG. 5 is a front view of the convertible scooter shown in FIG. 1.

FIG. 6 is a rear view of the convertible scooter shown in FIG. 1.

FIG. 7 is a top plan view of the convertible scooter shown in FIG. 1.

FIG. 8 is a bottom plan view of the convertible scooter shown in FIG. 1.

FIG. 9 is a top perspective view of a second configuration of a convertible scooter.

FIG. 10 is a bottom perspective view of the convertible scooter shown in FIG. 9.

FIG. 11 is a right side view of the convertible scooter shown in FIG. 9.

FIG. 12 is a left side view of the convertible scooter shown in FIG. 9.

FIG. 13 is a front view of the convertible scooter shown in FIG. 9.

FIG. 14 is a rear view of the convertible scooter shown in FIG. 9.

FIG. 15 is a top plan view of the convertible scooter shown in FIG. 9; and,

FIG. 16 is a bottom plan view of the convertible scooter shown in FIG. 9.

The broken lines are for the purpose of illustrating portions of the wagon that form no part of the claim.

1 Claim, 14 Drawing Sheets
